UNITED STATES PATENT OFFICE.

LUTHER R. FAUGHT, OF PHILADELPHIA, PENNSYLVANIA; MARY J. FAUGHT
ADMINISTRATRIX OF SAID LUTHER R. FAUGHT, DECEASED.

CORE FOR CASTING CAR-WHEELS.

SPECIFICATION forming part of Letters Patent No. 700,313, dated May 20, 1902.

Application filed October 2, 1901. Serial No. 77,330. (No model.)

To all whom it may concern.

Be it known that I, LUTHER R. FAUGHT, of Philadelphia, in the county of Philadelphia and State of Pennsylvania, have invented a 5 certain new and useful Improvement in Cores for Casting Car-Wheels, of which improvement the following is a specification.

This invention relates to the manufacture of railroad-car wheels of the type ordinarily 10 known as "loose" wheels, which are mounted upon their axles with the capacity of rotation independently thereof, and of loose wheels of other descriptions; and its object is to provide means whereby a device for holding 15 a loose wheel upon its axle, known as a "key-block," may be installed in operative position in the hub of the wheel when said key-block is of such form and dimensions as preclude its insertion therein through the 20 central bore or opening of the hub. Instances of key-blocks of the character referred to are exemplified in Letters Patent of the United States Nos. 687,453 and 687,454, granted to Luther R. Faught, his heirs or assigns, under 25 date of November 26, 1901.

To this end the invention, generally stated, consists in the combination of elements hereinafter described, and then pointed out in the claims.

30 The improvement claimed is hereinafter fully set forth.

In the accompanying drawings, Figure 1 is a transverse section through a core for the hub of a loose wheel, illustrating an application 35 of my invention, the section being taken on the line *a a* of Fig. 2; Fig. 2, a longitudinal central section through the same; Fig. 3, a transverse section through a core, showing a different form of the key-block, the section 40 being taken on the line *b b* of Fig. 4; and Fig. 4 a longitudinal central section through the same.

In the practice of the invention the core or internal mold of the wheel-hub is, as in ordinary practice, formed of sand or other suitable refractory and sufficiently-comminuted material and is baked or dried in a core-oven in the usual manner. As indicated by the dotted outlines, the wheel-hub for casting

which the core is designed is when cast provided with a central bore or opening closed at one end to receive the axle and with an annular oil-chamber surrounding the central bore and communicating therewith by lateral oil-passages. The core is made in corresponding form—that is to say, it comprises a central cylindrical body or stem 1, which forms the space for the bore of the hub, an annular rim 2, which forms the space for the oil-chamber, a transverse web 3, which connects the body and rim near the front of the body and forms the space surrounding the key-block, to be presently described, and lateral arms 4, which connect the rear or inner portion of the rim with the body and form the spaces for the rear or inner oil-passages. In constructing the core an annular space or cavity 14 is formed between the stem 1 and the rim 2, which cavity is closed on one side by the web 3 and is spanned on the other side by the arms 4. This cavity may be formed in any of the ways known to the art, as by placing an annular ring around the formed stem 1, then forming the rim 2, and after removing said ring forming the arms 4.

A key-block 8, which is preferably formed of cast steel and which when the wheel is cast fits and moves freely toward and from the axial line thereof in the space formed by the web 3 of the core, is seated in said web at 80 or near its periphery, the front face of the key-block being substantially flush or on a level with that of the web. As shown in Figs. 1 and 2, the key-block is of one of the forms illustrated in Letters Patent No. 687,453 aforesaid—that 85 is to say, a plate having its inner end segmentally recessed to fit on a neck or reduced portion of the axle and having a longitudinal recess 8^a extending from its inner end nearly to its top and a transverse passage 8^b, extending through said recess, these spaces being formed in the key-block for the purposes of lightening it and of affording a lateral vent for the mold in casting the wheel. The specific form of the key-block may, however, be 90 varied and does not constitute an essential of the present invention.

The setting of the key-block in or its tem-

porary incorporation with the core may be effected in any manner within the ordinary skill of the molder which is deemed most desirable. Thus, for example, the key-block 5 may be placed in the core-box and the damp sand rammed in around it, and wires may be inserted through the openings of the key-block, so as to hold it in place while the core is being baked, after which the meeting surfaces 10 of the key-block and the sand of the core, as well as the outer face of the key-block, may be painted over smoothly with common liquid blacking, thickly covering the parts and protecting the key-block from the molten iron in casting the wheel. If the core should at any point be comparatively thin, as at the rear of the key-block, a strip of asbestos paper or analogous strong and fibrous refractory material 15 may be inserted, as shown in Fig. 2. This strip will be reduced to the condition of powder by the heat of the molten iron, so that upon the agitation or jarring of the wheel after it has cooled it will break up and fall out through the central bore of the hub. In some cases it may be found convenient to attach the strip of asbestos paper to the key-block by shellac varnish before setting the key-block in the core, the strip 25 approximately covering the portion of the surface 30 of the key-block adjoining which the wall of the core is thin.

A main vent 6 extends substantially throughout the body of the core, and lateral vents 7, leading thereto, are formed in the web 3 and rim 2, one or more of the lateral vents passing into the interior space of the key-block 8. The escape of gases from all portions of the core and from the space within the key-block is thereby effectually provided for.

The core is held in positive position in the mold by a metal center support 9, which extends centrally into the body of the core for any desired distance from its outer end and is inserted in the core when green or wet before baking. The outer end of the support 45 is fitted in a step or bearing 10, which in molding the wheel is set upon a support on the pattern, which holds the step in central alignment while the sand is being tucked and rammed around it. When the pattern is withdrawn, the step remains enveloped in the sand of the mold and in this position receives and supports the main core, the center support 9 of the core dropping into a central bore in the step and resting on the lower portion thereof. The core is thereby truly aligned vertically, and when the cope or top section of the mold is closed down upon a print 1^a 50 on the inner end of the body of the core the set of the core is assured in all directions. It is of course understood that in casting the wheel the core stands vertically upon the base 10, with the print 1^a uppermost. The center support becomes fast in the wheel when cast 65 and is cut off inside and out in finishing the

hub. A transverse slot 10^a is formed in the step 10 in order to prevent disturbance of the setting of the core by sand which may fall into the central bore of the step, such sand 70 passing off through the slot without interfering with the adjustment of the center support 9 in the step.

The proper position of the key-block relative to the core is insured by a small stop- 75 core 11, which passes through the transverse passage 8^b of the key-block. The body of the core is preferably stiffened by a longitudinal metal supporting-rod 12, inserted in the body on the side of the axis thereof farther from the main vent 6, and lateral supports of wire 80 may also be placed in the web 3 between the lateral vents.

The core shown in Figs. 3 and 4 accords in all substantial particulars with that above 85 described and is illustrated for the purpose of exemplifying the employment of a different specific form of key-block, which in this instance accords with that set forth in Letters Patent No. 687,454 aforesaid. 90

I claim as my invention and desire to secure by Letters Patent—

1. The combination of a core having a central body or stem, an annular rim, a transverse web connecting the body with the rim, 95 at or near one end of the latter, and lateral ribs connecting the rim, at or near its opposite end, with the body, a key-block seated in the web of the core, supports for maintaining the core and key-block in normal 100 form and location, and main and lateral vents formed in the core.

2. The combination of a core having a central body or stem, a transverse web, and a print at one end, a center support fitted in 105 and projecting from the body of the core at the end opposite the print, a step or bearing in which said center support is fitted, and a key-block seated in the web of the core.

3. The combination of a core having a central body or stem and a transverse web, a key-block seated in the web of the core and having internal spaces or passages, a center support fitted in and projecting from the body of the core, and a stop-core fitting in the web of 115 the core and in one of the passages of the key-block.

4. The combination of a core having a central body or stem and a transverse web, a key-block seated in the web of the core and having internal spaces or passages, a main vent 120 extending throughout the major portion of the length of the body of the core, and a lateral vent formed in the web of the core and connecting one of the internal spaces of the 125 key-block with the main vent.

5. The combination of a core having a central body or stem and a transverse web, a key-block seated in the web of the core, and a strip of refractory material, as asbestos paper 130 or the like, fitted in the core adjacent to the key-block.

6. The combination of a core having a central body or stem and a transverse web, a center support fitted in and projecting from one end of the body of the core, a key-block seated in the web of the core, a main vent extending throughout the major portion of the length of the body of the core, and a lat-

eral vent formed in the web of the core and leading into the main vent.

LUTHER R. FAUGHT.
